UNITED STATES PATENT OFFICE

2,250,755

BOOK AND BINDING FOR SAME

Emil N. Farkas and Frank F. Farkas, Chicago, Ill.

Application September 6, 1938, Serial No. 228,478

3 Claims. (Cl. 281—29)

The invention relates generally to books and more particularly to an improved construction for securing the pages in assembled relation.

Our invention has among its objects the production of a book or booklet of the kind described, particularly adapted for pamphlets, catalogues, and the like which is simple in construction, durable, attractive, efficient and relatively inexpensive.

Another object of the invention is the production of such a device wherein the cover is so constructed and shaped that it forms the retaining means for holding the pages in place without the use of additional mechanical bindings.

Another object of the invention is the production of such a device wherein the retaining means is so shaped that the pages will readily turn on the retaining means without binding or sticking, etc.

A further object of the invention is the production of such a device wherein a single cover forms the retaining means for the leaves which may be assembled without the use of glue or other material, the means and cover being so constructed that they interlock with one another.

Another object of the invention is the production of a book wherein the covers independently of each other pass through and secure the pages in assembled relation.

Many other objects and advantages of the invention herein shown and described will be obvious to those skilled in the art from the disclosure herein given.

To this end our invention consists in the novel construction, arrangement and combination of parts herein shown and described and more particularly pointed out in the appended claims.

In the drawing wherein like reference characters indicate like or corresponding parts:

Fig. 1 is a plan view of a book embodying the present invention with a portion thereof broken away;

Fig. 2 is a sectional view taken on the line 2—2 of Fig. 1;

Fig. 3 is a sectional view taken on the line 3—3 of Fig. 1;

Fig. 4 is a plan view of a book with a portion broken away illustrating a slightly modified form of construction and one manner in which the elements may be interlocked without the use of glue or other material;

Fig. 5 is a sectional view taken on the line 5—5 of Fig. 7;

Fig. 6 is a plan view of the cover and retaining means of the book illustrated in Fig. 4;

Fig. 7 is a plan view of a book with a portion broken away illustrating a slightly different form of interlocking the retaining means and cover;

Fig. 8 is a sectional view taken on the line 8—8 of Fig. 7; and

Fig. 9 is a plan view similar to Fig. 6 of the cover and retaining means illustrated in Figs. 7 and 8.

Referring to the drawing, and more particularly to Figs. 1, 2 and 3, 1 represents a cover formed of suitable material of a size to extend across the adjacent face of the pages 2, the latter being provided with apertures 3 therein adjacent one end of said pages, the apertures on the respective pages being similarly positioned so that they will be aligned when the pages are stacked in assembled relation as shown in Fig. 2.

Extending from the end of the cover adjacent the apertures 3 are a plurality of tongues 4, the cover 1 being cut adjacent the tongues as shown at 5 of Fig. 3 so that the tongues begin at a point spaced from the edge of the cover, with the result that the lateral dimensions of the cover are substantially the same as that of the leaves. However, if desired the tongues may begin at the edge of the cover. These tongues are bent adjacent their origin transversely to the cover and extend through the apertures 3. The tongue then passes around the adjacent ends 2' of the pages 2 back to the cover 1, the latter being provided with a slit 6 of a size to receive the end 7 of the tongue 4. The end 7 is passed through the slit and extends along the inside face of the cover, as shown in Figs. 2 and 3. If desired, glue or other means may be employed to secure the end 7 of the tongue to the adjacent face of the cover although the same will be held sufficiently by the frictional engagement between the tongue and cover as well as between the leaves and the ends of the tongues. It will be noted that this construction provides a very efficient retaining means, there being no possibility of the leaves catching or sticking.

If desired, the tongues 4 may be constructed to positively interlock with the cover so that glue or other means is unnecessary. Likewise while we have shown the retaining means and cover as formed from a single sheet of material, it might, in certain types of books, be desirable to form the cover from several different materials. A construction embodying both of these features is illustrated in Figs. 4, 5, and 6, the retaining

means being formed from one piece of material and the cover proper from another, with the retaining means so constructed that the free ends of the tongues will interlock with the remaining portion of the means. In the construction illustrated, the cover proper 11 is of approximately the same size as the leaves and secured to the cover is a piece of suitable material 11' from which the tongues 14 are formed. This construction would be advantageous, for example, when the cover proper 11 is to be formed from relatively stiff material, whereby said cover could be formed from such material and the portion 11' carrying the tongues could be formed from more pliable material, this providing a cover and retaining means, as a unitary structure, in which both the cover proper and the retaining means are formed out of materials most suitable for each. As shown in Fig. 6, the tongues 14 are provided with two slits 15 and 16, the slit 15 being positioned on one side of the respective tongue, intermediate the ends thereof, and as shown, extending approximately half way through the tongue itself, the slit 16 being positioned on the side of the tongue opposite the slit 15. Obviously, the exact size and positions of the slits will depend upon the relative proportions of the tongues used, and the size of the loop, formed by the tongues, desired. As shown in Fig. 5 the tongues 14 are passed through the apertures 3 in the leaves 2 and cover 9 as in the other constructions and passed around the ends 2' of the leaves, after which the portions 18 are sprung slightly to allow the end of the tongue 17 to engage the slit 16, adjacent the slit 15 on the tongue, as shown in Fig. 4, thereby interlocking the tongues with the portion 11' and therefore with the cover 11.

The construction shown in Figs. 7, 8, and 9 is somewhat similar to that just described, but provides a more positive locking action. As shown in Figs. 7, 8 and 9, particularly Fig. 9, the cover 21 is provided with tongues 24, the tongues being provided with slits 25 corresponding to the slits 15. However, the slits 25 are spaced from the sides of the tongue and a smaller secondary tongue 29 is cut from a portion of the tongue 24 intermediate the slit 25 and one edge of the tongue 24. A second slit 26 corresponding with the slit 16 is also provided adjacent the juncture of the tongue 24 and the cover 21. It will be noted that the slit 30 severing the tongue 24 from the portion 28 of the cover 21 intersects the slit 26 intermediate the ends of the latter, so that the width of the tongue decreases from the outer edge of the portion 28 toward the slit 26. Thus when the tongue is brought through the leaves around the ends of the pages and back to the cover similarly to the tongues 14, and the tongue is engaged with the notch 26 adjacent the notch 25, the portion 28 adjacent the slits 26 and 30 will overlap the edge of the tongue as shown at 31 in Fig. 7.

Referring to Figs. 7 and 8, it will be noted that the small secondary tongue 29 is positioned adjacent the inner end of the tongue 24 while the extreme outer end 27 of the tongue is positioned adjacent the inner face of the cover 21. As the tongue 29 overlaps the inner portion of the tongue 24 adjacent the cover and extends through the apertures 3 in the leaves 2, the latter will tend to press the tongue 29 against the tongue 24

thereby providing added frictional engagement between the parts and lessening the strain on the locking means.

It will be noted from the above description that we have provided a book in which the cover or covers provide the retaining means for maintaining the leaves in assembled relation, wherein said means is so constructed that the individual leaves will at all times freely turn thereon without binding or sticking. While the covers carrying the retaining means have been illustrated as substantially coextensive with the leaves, obviously, the cover may be longer or smaller than the leaves as desired. Likewise, we have provided novel means for interlocking the retaining elements in position without the use of glue or other additional material.

Having thus described our invention, it is obvious that various immaterial modifications may be made in the same without departing from the spirit of our invention; hence, we do not wish to be understood as limiting ourselves to the exact form, construction, arrangement and combination of parts herein shown and described or uses mentioned.

What we claim as new and desire to secure by Letters Patent is:

1. In a device of the kind described, a plurality of leaves, a flexible cover member for said leaves, said leaves having a plurality of apertures therein adjacent one end thereof, said cover member having a plurality of slits therein and extended at one end to form a plurality of tongues integrally connected with said member, said slits being positioned adjacent to and aligned with said tongues, the latter being bent transversely to said cover at their juncture therewith and passing through the apertures in said leaves, the free ends of said tongues passing around the ends of said leaves adjacent the juncture of said tongues and cover to form substantially complete rings, and through the slits in said cover.

2. In a device of the kind described, a plurality of leaves, a cover member for said leaves, said leaves having a plurality of apertures therein adjacent one end thereof, said cover member having a plurality of pliable tongues extending from said member, said tongues being bent transversely to said cover member at their juncture therewith, and passing through the apertures in said leaves, the free ends of said tongues passing around the adjacent ends of said leaves to adjacent their origin to form substantially complete rings, and means formed on said cover and tongues for interlocking the same together.

3. In a device of the kind described, a plurality of leaves, a cover member for said leaves, said leaves having a plurality of apertures therein adjacent one end thereof, said cover member having a plurality of tongues extending from said member, and each having a slit adjacent said juncture, and a second slit spaced therefrom on the opposite side of the respective tongue, said tongues being bent transversely to said cover member adjacent said juncture and passing through the apertures in said leaves, the free ends of said tongues passing around the adjacent ends of said leaves, and extending through said first mentioned slit, adjacent said oppositely disposed slit.
